UNITED STATES PATENT OFFICE.

ALF E. ANDERSON, OF MILTON, MASSACHUSETTS, ASSIGNOR TO ALBERT & J. M. ANDERSON MANUFACTURING COMPANY, OF BOSTON, MASSACHUSETTS, A CORPORATION OF MASSACHUSETTS.

ELECTROMAGNET.

Application filed April 23, 1925. Serial No. 25,305.

This invention relates to an electromagnet provided with an armature and has for its object to provide the electromagnet with an armature which will respond to electric currents of varying or different strengths. To this end, the electromagnet is provided with an armature having members capable of forming an air gap between them and preferably arranged so that the width of the air gap may be varied by the adjustment of one armature member with relation to the other and thereby increase or decrease the pull or attraction of the electromagnet upon the armature and thus adjust the electromagnet to meet variations in conditions of use, as will be described.

The invention is especially applicable to electromagnets employed for controlling the operation of other apparatus, such, for instance, as electric circuit controllers, which it is desired should respond to a given strength of current under certain conditions of use.

These and other features of this invention will be pointed out in the claims at the end of this specification.

Fig. 1 represents in elevation and section one form of electromagnet embodying this invention, the members of the armature being shown in contact, and

Fig. 2, a like view with the members of the armature separated by an air gap.

In the present instance, the invention is shown as embodied in that form of electromagnet known as a solenoid, which is provided with an armature in the form of a core.

The solenoid may be of any desired construction and is herein shown as composed of a coil or winding *a* located in a casing or shell *b* having a head *c* through which is extended a rod *d* having a reduced threaded portion 10. The rod *d* has mounted upon it a core or armature comprising a plurality of members, herein shown as two in number and marked 12, 13. The member 12 is mounted on the threaded portion 10 and bears against a shoulder 14 and is forced against said shoulder by a nut 15 on the threaded portion 10. The member 12 will be herein referred to as a fixed member. The member 13 is provided with a threaded bore which engages the threaded portion

10 and is capable of being adjusted on said threaded portion 10 toward and from the fixed member 12. The member 13 is provided at its upper end with a socket 16 for the reception of the nut 15 when the member 13 is in contact with the member 12 as represented in Fig. 1. The member 13 is also provided at its lower end with a socket 17 for the reception of a nut 18, which locks the member 13 in its adjusted position on the threaded portion 10 of the rod *d*, as represented in Fig. 2.

When the armature members are in contact with each other, as represented in Fig. 1, the electromagnet exerts a maximum attraction or pull upon the armature and responds to a predetermined strength of current flowing through the magnet to effect the desired movement of the armature.

When however the armature member 13 is moved away from the member 12 so as to provide an air gap 20 between said members, as represented in Fig. 2, the attractive force or pull upon the armature is decreased, so that it will require a greater strength of current to effect the desired movement of the armature.

By adjusting the member 13 into different positions with relation to the member 12, the air gap 20 may be made of different widths or sizes to enable the armature to respond to different strengths of current.

An electromagnet of this character is especially useful in connection with apparatus whose operation is controlled by the said electromagnet, such, for instance, as circuit controllers or switches and the like.

In the present instance, such apparatus is represented by a toggle comprising the members 30, 31, whose center pin 32 is connected by a link 33 with the rod *d*, so that when the electromagnet is energized and its armature or core is attracted and moved upwardly for a predetermined distance, the toggle is moved from its straightened or closed position into its inclined or broken position, Fig. 1, with attendant operation of the apparatus represented by the toggle.

In the present instance, the upward movement of the armature or core is limited by the head *c* with which the fixed member 12 is brought in contact.

As herein shown, the rod *d* is provided at

its upper end with a head 34 having an opening 35 through which is extended a pin 36 which connects the lower end of the link 33 with a forked lever 37 pivoted at 38 to a lug 39 on the magnet casing or shell 7. The pin 36 co-operates with the upper wall 40 of the head 34 when the core or armature is moved downward and with the lower wall 41 of said head when said core is moved upwardly.

To illustrate the usefulness of an electromagnet, such as herein shown and described, let it be assumed that the electromagnet is designed to function at two amperes, and that when connected with the apparatus represented by the toggle 30, 31, the conditions are changed so that a greater or less current is required to operate the electromagnet and the apparatus controlled thereby.

Assume for instance that when the armature is adjusted so as to be provided with an air gap 20 of one-half inch, it will respond to a current of two amperes and operate the apparatus controlled by it in the proper manner.

Assume also that a condition arises in the apparatus controlled by the electromagnet and represented by the toggle 30, 31, whereby a current of greater or higher strength, as for instance two and two-tenths (2.2) amperes is required to operate the electromagnet and the apparatus controlled by it. Under these latter conditions, the operator adjusts the armature member 13 so as to increase the air gap 20 and thereby decrease the pull of the electromagnet upon the armature and allow the current flowing through the electromagnet to build up to two and two-tenths (2.2) amperes and thus enable the apparatus controlled by the electromagnet to be operated the same as it is operated when the conditions of the apparatus are such that it is operated with a current of two amperes.

If on the other hand, the conditions of use are such that the apparatus is operated by a current of less strength, as for instance, one and eight-tenths (1.8) amperes, the armature member 13 is adjusted so as to decrease the air gap 20 and thereby increase the pull of the magnet and cause the apparatus controlled by the electromagnet to be operated as it is designed to operate with the normal air gap represented by the two ampere current.

It will thus be seen that by lengthening or shortening the air gap between the members of the armature, the apparatus controlled by the electromagnet is caused to operate in the proper manner.

It will further be observed that by widening or increasing the air gap, the pull or attraction of the electromagnet upon the armature is weakened or diminished, and by diminishing or closing the air gap, the pull

or attraction of the electromagnet is increased.

In the present instance, the invention is shown in an electromagnet of the solenoid type, but it is not desired to limit the invention in this respect, as it is equally applicable to the armatures of other types of electromagnets.

What I claim is:

1. A solenoid provided with a rod having a threaded portion of smaller diameter forming a shoulder, a core member on said threaded portion, a nut to secure said core member in fixed position on said rod, a second core member in threaded engagement with the threaded portion of said rod to move as one piece with the fixed core member when said solenoid is energized and adjustable thereon toward and from said fixed core member to form air gaps of different sizes, and a nut to retain said second core member in its adjusted position.

2. A solenoid provided with a rod, a core member mounted thereon and having a fixed relation thereto, and a second core member mounted on said rod to move longitudinally thereon toward and from said fixed member to form an air gap between them and affixed to said rod to maintain said air gap and move as one piece with said fixed core member when said solenoid is energized.

3. An electromagnet provided with an armature having members separated by an air gap, and means for connecting said members together to move as one piece and maintain the air gap between them when said electromagnet is energized.

4. An electromagnet provided with an armature having members capable of forming an air gap between them, and means for connecting said members together to permit one of said members to be moved to vary the size of said air gap and to maintain said air gap and permit both members to be moved as one piece with the air gap between them when said electromagnet is energized.

5. An electromagnet provided with an armature having members separated by an air gap and connected together to maintain the air gap and cause the armature to be moved as one piece in response to a current of given strength flowing through the electromagnet.

6. An electromagnet having an armature provided with members adjustable with relation to each other to form between them air gaps of different sizes and secured in their adjusted position in fixed relation to maintain the selected air gap while the armature is being moved and cause the armature to be moved as one piece in response to a current of given strength flowing through the electromagnet.

7. An electromagnet provided with an armature having members capable of form-

ing an air gap between them, a support for said members on which one of said members is movable with relation to the other to form an air gap between them, and means for securing said movable member in fixed relation to said support and to the other of said members to maintain the air gap be-

tween said members and cause them to be moved as one piece in response to a current of given value flowing through the electro-¹⁰ magnet.

In testimony whereof, I have signed my name to this specification.

ALF E. ANDERSON.
